WOVEN ELASTIC BINDING STRIP

Halfdan J. Nordseth, San Francisco, Calif., assignor to United Elastic Corporation, Easthampton, Mass., a corporation of Massachusetts

Application November 10, 1939, Serial No. 303,749

1 Claim. (Cl. 138—384)

This invention relates to the manufacture of garments and other goods from fabrics, and is especially concerned with the materials used in making the seams by means of which the parts of such articles are secured together.

In stitching together the sections of a garment, especially if it includes elastic fabric, it is necessary to run in four lines of stitches to each seam in order to produce a really secure union which will present a satisfactory appearance. This invention aims to improve the construction of seams and the materials of which they are made, with a view to reducing the work involved and also producing a more satisfactory construction. An especially important feature of the invention resides in a novel binding material designed for use as an element of a seam.

The nature of the invention will be readily understood from the following description when read in connection with the accompanying drawings, and the novel features will be particularly pointed out in the appended claim.

In the drawings.

Figure 1 is a perspective view of a short length of binding embodying a feature of this invention;

Figs. 2 and 3 are plan and edge views, respectively, of a slightly different form of binding material, also constructed in accordance with the invention;

Figs. 4 and 5 are perspective views showing the manner in which sections of a garment, or the like, may be united with the aid of binding strips such as those shown in Figs. 1, 2 and 3;

Fig. 6 is a sectional view through the strip shown in Fig. 1 on a large scale; and

Figs. 7, 8, 9 and 10 are perspective views showing typical ways in which the binding strips provided by this invention may be used in making different garments.

Referring first to Figs. 1 and 6, the binding there shown comprises upper and lower plies or layers, the marginal portions of which are free from each other while their central portions are interwoven by means of binder warps into an integral structure and, consequently, unite the marginal flanges or lips permanently together. In the drawings the intermediate portion of the strip is indicated at 2, the upper flanges at 3 and 4, and the lower flanges at 5 and 6, respectively. While this binding may be made of non-elastic yarn or thread, it is preferable for most purposes to include rubber warps, such as those shown at 7, in its construction so that it will have a high degree of longitudinal elasticity. If

desired, rubber filling threads may also be included, either with or without rubber warps, in order to give the strip a lateral elasticity.

Such a product may conveniently be made in a double-shuttle narrow wear loom, the two shuttles laying in the filling threads in the two plies or layers, while the harnesses are operated to form suitable sheds for producing the two plies or layers, at the same time manipulating the binder warps to unite the two plies of the central section 2 to each other.

In the particular form of binding strip shown in Figs. 1 and 6, the flanges and layers or plies are of the same length, but for some purposes it is preferable to make one layer considerably narrower than the other, and such a binding strip is illustrated in Figs. 2 and 3. In this strip the intermediate section 2 is extremely narrow, the two plies being united by only a very few binder warps.

A typical method of using the binding A shown in Fig. 1 is illustrated in Fig. 4. Since the two pairs of flanges projecting from the opposite edge of the central portion 2 of the strip lie parallel to each other and are free from each other, they provide slots between them into which the adjacent edges of sections of fabric 8 and 9 forming, for example, parts of a garment, may be inserted. The flanges associated with the respective sections are then secured to them by lines of stitches, the nature of which is determined by the character of the work. For example, if the goods are of substantially non-elastic material, then plain stitching may be used, such as that shown at c in Fig. 4. On the other hand, if the goods are of stretchable or elastic material so that it is desired to take advantage of the elasticity of the binding, then a staggered stitch seam, such as that shown at d in Fig. 4, is preferable. In either event, the raw edges of the fabric are effectively concealed by the binding material. Two sewing operations only need be performed, both lines of stitches c being run in at one operation in a double-needle machine, and the staggered stitching d being produced at another operation. The goods thus are firmly anchored to the binding, and a neat and attractive seam is produced.

In using the binding b, Figs. 2, 3 and 5, essentially the same procedure may be followed. Here the staggered stitched seams e and f may be employed not only to secure the two sections of fabric 10 and 12 to each other, but also to bind the outer or selvage edges of the flanges 5' and 6' in place. The middle stag-

gered stitch seam *g* secures the inner edges of the fabric webs *10* and *12* to the flanges *3'* and *4'* and may either be made to straddle the entire width of this narrow ply or to approximately do so, as shown in Fig. 5. In either event the fabric strip *10* is secured between the flanges *4'* and *6'* by the seams *e* and *g* and the other section *12* of fabric similarly anchored in the same manner by the lines of stitches *f* and *g*. This arrangement is particularly useful when the parts *10* and *12* consist of elastic fabrics.

Fig. 7 shows the binding *a* forming part of a seam by means of which sections of knitted, and therefore stretchable and somewhat elastic materials, forming portions of a pair of bathing trunks, are secured together. A somewhat similar use for this material is shown in Fig. 10 where it connects the waist and pants of an article of underwear.

Fig. 8 shows these bindings connecting a non-elastic section *15* of a corset with elastic sections *16* and *17*.

In Fig. 9 a binding strip *A* connects the waist and skirt portions of a dress. While the fabrics of which these parts of the garment are made may be non-elastic, they are gathered, as indicated, and secured together through the medium of the binding by a stitched seam, the details of which are not shown, but which makes the elasticity of the binding available in accommodating

the stretch provided by the gathered construction at this portion of the garment.

These are merely illustrative of the many uses which may be made of the novel binding provided by this invention. It should be understood, however, that in stitching the binding to elastic or gathered goods, the stitching is performed with both the goods and the elastic binding strip stretched and elongated so that the subsequent contraction of the goods will restore them to normal dimensions, the degree of initial elongation being sufficient to provide the desired degree of stretch during the use of the garment.

Having thus described my invention, what I desire to claim as new is:

An elastic binding strip for joining two fabrics together in edge to edge relationship, comprising a relatively narrow strip of woven fabric comprising two layers of fabric positioned one above the other, portions of said layers spaced from the selvage edges of said layers being interwoven with each other into an integral structure leaving the four selvage portions of the layers free and projecting from opposite edges of said central interwoven portion, all four of said free margins being woven selvage edges and the strip including elastic threads in the weave thereof running parallel to said edges and imparting a substantial degree of elasticity to the strip.

HALFDAN J. NORDSETH.
